CORYDON L. BUSHNELL, OF JEFFERSON, OHIO.

Letters Patent No. 98,664, dated January 11, 1870.

IMPROVEMENT IN CANE AND WHIP COMBINED.

The Schedule referred to in these Letters Patent and making part of the same.

To all whom it may concern:

Be it known that I, CORYDON L. BUSHNELL, of Jefferson, Ashtabula county, Ohio, have invented a new and useful implement, to be used either as a cane or whip, and styled a "Cane-Whip;" and I do hereby declare that the following is a full description thereof, reference being had to the accompanying drawings, and to the letters of reference marked thereon.

Figure 1 is a perspective view, showing the cane and whip combined.

Figure 2 is a central sectional view through the cane, showing the whip closed therein.

Figure 3 is a central vertical section of the head of the whip.

Figure 4 is a perspective view of the lower end of the cane, the tip-thimble having been removed.

The barrel A may be manufactured of nearly all the known material used for canes, and of the desired length and size of common walking-sticks, with a tube, B, the entire length, of about one-half inch bore at the but, and one-fourth of an inch at the small end.

A metal plug, C, one and one-fourth of an inch long, with a screw-thread, is firmly fixed into the small end of the tube B, extending therefrom three-fourths of an inch, and which extension receives the tip-thimble D.

A metal thimble, E, two inches long, is let into the but, so that the inside of the tube B and the inside

of thimble E will form a plane, even surface, the thimble extending from the but about three-eighths of an inch, with a screw-thread, or other means of fastening, on the head F.

The bow G is made in the usual manner and material of ordinary whips, with a metal ferrule, H, two inches long, fastened thereon.

To adjust the implement for a cane, place the bow G, tip foremost, into the tube B, screw on the head F and tip-thimble D.

When used as a whip, remove head F and tip-thimble D, draw out bow G, and screw it on to plug C, place tip-thimble D into tube B for safe keeping, and put on head F.

What I claim as my invention, and desire to secure by Letters Patent, is—

A convertible cane and whip, so arranged that when closed as a cane, it shall consist of the barrel A, head F, and ferrule D, the said barrel enclosing its bow G, and, when arranged as a whip, said whip to be formed by removing the bow from barrel A, and fastening the same upon its screw-thread C, as shown and described, and for the purpose set forth.

C. L. BUSHNELL.
